Primary Examiner—Raphael Barkai*Attorney, Agent, or Firm*—Michael T. Marrah; Grant D. Kang; Gregory E. Upchurch[57] **CLAIM**

I claim the ornamental design for the small toy storage tote with integrated toy size tester, as shown and described.

DESCRIPTION

FIG. 1 is a rear perspective view of a small toy storage tote with integrated toy size tester showing my new design;
FIG. 2 is the claimed design from a side view;
FIG. 3 is the claimed design from the side opposite that shown in FIG. 2;
FIG. 4 is the claimed design from the rear view;
FIG. 5 is the claimed design from a front view;
FIG. 6 is the claimed design from a top view; and,
FIG. 7 is the claimed design from a bottom view.
